WRENCH

Willis E. Williams, New Orleans, La.

Application March 15, 1944, Serial No. 526,536

2 Claims. (Cl. 81—90)

1

This invention relates to a wrench particularly designed to screw a coupling flange onto a shaft or pipe, or to unscrew it therefrom. It is a reversible wrench of the ratchet type.

Wrenches of this type and for this purpose are known, but insofar as applicant is aware, these are characterized by having spring yielding pawls engageable with open ratchet teeth.

Spring biased pawls are difficult or unhandy to reverse, inasmuch as the spring and pawl must either be severally disassociated and replaced in reverse position, or the spring and pawl must be reversed as a unit, necessitating the provision of an additional element, a common reversible carriage for both spring and pawl. Besides, a spring actuated pawl is readily clogged with grease and debris, requiring frequent cleaning to keep it operative. Open ratchet teeth, too, are subject to becoming obstructed by grease or other foreign matter, preventing proper interdigitation of the pawl therewith, and if made cheaply, as of brittle cast material, are liable to breakage.

One of the objects of the present invention is to provide a wrench of the class described, having a reciprocable handle member, and a member operated thereby unidirectionally in either direction, having means engageable with the bolt holes of the flange coupling, one of said members carrying a pawl which is reversible but unyieldable, and projects laterally with respect to the plane of rotation of the handle member, and in which the usual ratchet teeth are substituted by a circular series of peripherally closed apertures in the handle operated member, opening laterally in the face of said member adjacent the pawl, the latter member normally being spring biased to lie in the path of movement of the pawl, and being forced out of the path of said pawl against the bias of the spring by camming action against the slope of the pawl to permit unidirectional slippage between the pawl and the apertured member.

Another object of the invention is the provision of a plurality of pawls at uniformly spaced intervals, whereby uniform parallel relative displacement between the pawl and ratchet members is secured.

Other objects of the invention will appear as the following description of a preferred and practical embodiment thereof proceeds.

In the drawing throughout the several figures of which the same reference characters have been used to denote identical parts:

Figure 1 is a plan view of the wrench, part of the handle member being omitted;

2

Figure 2 is a diametrical cross-section taken along the line 2—2 of Figure 1;

Figure 3 is a similar cross-section taken along the line 3—3 of Figure 1;

Figure 4 is an axial cross-section taken through one of the reversible pawls along the line 4—4 of Figure 2.

Referring now in detail to the several figures, the numerals 1 and 2 represent, respectively, a disk or ratchet member and a handle or pawl carrying member, the latter extending diametrically across the rear face of the disk 1. The disk and handle member are pivoted along a common axis by means of a pin 3, which passes through aligned apertures in said members. The pin 3, as shown, has a conical head 4 seated in a countersink in the disk 1, and at its rear end it has a spring retaining head or knob 5. A spring 6 surrounds the pin 3, being confined under compression between the knob 5 and the rear face of the handle member 2. Its normal function is to keep the disk 1 pressed yieldingly toward the handle member 2. A washer 7 between said disk and handle member minimizes the friction between said members. The disk 1 has a non-adjustable pin 8 projecting from its front face and an adjustable similar pin 9 which may be selectively inserted in any one of the radially arranged apertures 10, 10', 10² which are on opposite sides of the axis of rotation from the non-adjustable pin 8. The pins 8 and 9 are adapted to fit into the bolt holes of the coupling flange which it is desired to secure or remove.

The pawls may be on either of the members 1 or 2, and the ratchet on the other member. As here shown, the pawls are carried by the handle member and the ratchet by the disk 1. The pawls 11 and 12, as shown, are two in number, equally spaced on opposite sides of the axis of rotation of the handle member 2. Each pawl consists of a head 13 having a sloping face 14 and an abrupt face 15, the latter being perpendicular to the plane of rotation of the handle member. The head 13 is at the inner end of a shank 16 journaled in a bearing aperture in the handle member 2. The opposite end of the pawl consists of a plate 17 fixed with respect to the shank 16 and preferably bearing frictionally against the handle member 2. The plate has a preferably non-round projection 18 adapted to be engaged by the fingers or by a tool, depending upon the frictional resistance between the plate 17 and handle member, for reversing the position of the pawl. When in operative position, both pawls will have the same direction of

orientation to produce either forward or backward movement of the disk 1.

The disk 1 is provided with a circular series of spaced apertures 19 of such size as to receive the heads of the pawls 11 and 12. Normally, the spring 6 holds the disk 1 in the path of movement of said pawls. When the handle is moved in a direction to bring the abrupt faces 15 of the pawls against the adjacent sides of the apertures 19, the disk 1 is rotated in that direction. When the handle 2 is moved in the opposite direction, the sloping faces 14 of the pawls cam against the adjacent edges of the openings 19 and force the disk 1 away from the handle member 2 against the bias of the spring 6, until the disk 1 is out of the path of movement of said pawls, permitting the latter to slide against the adjacent face of said disk until they enter adjacent apertures. Thus, on the retrograde movement of the handle member 2, the disk 1 remains stationary. Its progress is thus a step by step movement. When the direction of the unidirectional movement of the disk 1 is to be reversed, the knob 5 is pressed manually to bring the disk 1 out of the path of movement of the pawls. The position of the latter is then reversed by applying the fingers or a wrench to the non-round projections 18. The knob 5 is then released and the wrench is in condition to operate reversely.

It is obvious from the above description that the pawls are of simple construction, devoid of springs which might clog with grease or other matter and render the pawls inoperative, and that their adjustment from forward to reverse position is effected with utmost simplicity. It is also apparent that the apertures 19 are continuously framed on all four sides by the material of the disk 1, so that they are not apt to clog with grease, and are structurally stronger than the open teeth usually employed, and not subject to breakage. Consequently, the disk 1 may readily be made of brittle material such as castiron, with minimum risk of breakage.

Another advantage of the subject construction is that there are no radially extending open teeth, nor is there any radially positioned pawl to become fouled with foreign bodies, or broken by virtue of their exposed position.

While I have in the above description disclosed what I believe to be a preferred and practical embodiment of the invention, it will be understood to those skilled in the art that other arrangements of the parts or modification of the details of construction are within the scope of the appended claims.

What I claim as my invention is:

1. A flange wrench comprising a circular flange engaging disk having diametrically opposed bolt hole engaging elements projecting from its outer face and radially adjustable, a handle member extending diametrically across the inner face of said flange engaging disk, a pin at the center of said disk pivotally connecting said disk and handle member, a circular series of holes through said disk coaxial therewith constituting a ratchet, reversible pawls journaled at diametrically opposite points and held against axial movement in said handle member movable against the inner face of said handle member and registerable with said series of ratchet holes, said pawls having inclined cam faces, said pin extending through an aperture in said handle member and beyond, a spring surrounding the extended portion of said pin, a head on said pin retaining said spring in compression against said handle member, said spring having a range of compression movement equal at least to the height of said pawls whereby when they cam out of said ratchet holes said disk and handle member are forced apart sufficiently to permit passage of said pawls therebetween.

2. A flange wrench as claimed in claim 1, said pawls having portions on the outside of said handle member frictionally engaging said handle member and forming a finger or tool grip.

WILLIS E. WILLIAMS.
